[57] **CLAIM**

The ornamental design for a rod for a rice flail, as shown and described.

DESCRIPTION

FIG. 1 is a front-left-top perspective view of a rod for a rice flail, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reduced perspective view showing an embodiment of the claimed design, wherein the broken lines are shown for illustrative purposes only and form no part of the claimed design.
